(57) **CLAIM**

The ornamental design for a movable mount for electronic devices, as shown and described.

DESCRIPTION

FIG. 1 is a first side, top and front perspective view of a movable mount for electronic devices embodying the new design;

FIG. 2 is a second side, bottom and front perspective view thereof;

FIG. 3 is a first side, top and back perspective view thereof;

FIG. 4 is a top view thereof;

FIG. 5 is a bottom view thereof;

FIG. 6 is a second side view thereof;

FIG. 7 is a first side view thereof;

FIG. 8 is a front view thereof;

FIG. 9 is a back view thereof; and,

FIG. 10 is a first side and front perspective view of an alternate position thereof.

The uniform repeating broken lines depict portions of a movable mount for electronic devices in which the claimed design is embodied and form no part of the claimed design.
